UNITED STATES PATENT OFFICE.

JOEL E. GILES, OF JACKSON, MICHIGAN.

GRAIN-BINDER.

SPECIFICATION forming part of Letters Patent No. 322,439, dated July 21, 1885.

Application filed October 13, 1883. (No model.)

To all whom it may concern:

Be it known that I, JOEL E. GILES, of Jackson, in the county of Jackson and State of Michigan, have invented a new and useful Improvement in Grain-Binders; and I do hereby declare that the following is a full, clear, and exact description of the same.

My invention relates to automatic grain-binders, and has for its object, first, to adapt the binding mechanism to an ordinary reaper, the binder being an attachment capable of removal, leaving the machine for separate use. The second object is to secure complete separation of the gavels by making the separation between the cut and the uncut grain; and, generally, in addition to these objects, my purpose has been to reduce the weight, simplify the construction, improve the working of the parts in respect to ease of action and durability, to avoid the shelling of the grain in process of reaping, and, finally, to lessen the cost of the machine to the farmer. The new features and combinations are pointed out in the claims.

In the accompanying drawings, Figure 1 represents a plan view of a reaper with the binding attachment in place. Fig. 2 is a perspective view showing part of the fixed platform with the gate for enlarging the discharge-passage for the grain and the mechanism for operating the gate; Fig. 3, a vertical section on line $x x$ of Fig. 1, viewed from the left-hand side of the machine. Fig. 4 is the same view with the parts in changed position. Fig. 5 shows in perspective details of the binder platform and conveyer. Fig. 6 is a rear elevation of the binder attachment. Fig. 7 is a rear elevation on a larger scale of parts of the tying mechanism. Fig. 8 is a side elevation of the frame which carries the tying mechanism, with a face view of the driving-wheel therefor. Fig. 9 is a perspective view of the stripper and knife detached. Fig. 10 represents in main outline the left-hand side of the machine, showing the wheels which drive the carrier and tying mechanism and the needle with its connection to the wheel. Figs. 11, 12, 14, and 15 are side views of the knotter and holder, showing the method of tying the knot. Fig. 13 is a perspective view of the knotter. Fig. 16 is a plan view, partly in sec-

tion, of the knotter and stripper and cutter; and Fig. 17 is a front elevation of the same.

The binding attachment consists of a removable platform, on which is mounted the binding mechanism, said platform being adapted to an ordinary form of reaper having a quadrant-platform and rotary rakes to deliver the grain in gavels at the side of the platform. From such a reaper it may be detached when the binding attachment is not required, and thus the same machine be made to serve the purposes heretofore accomplished by two independent machines; but it is rigidly attached to the reaper-platform, in the manner herein-after explained, and is further supported by a caster-wheel, so that a flexible pole may be used and the weight and jolting of the machine taken from the necks of the horses. This removable platform is shown at A, and includes a small rectangular platform, a, which affords a rear extension to the main or permanent platform of the reaper. The platform A rests upon sills c c, which extend underneath the permanent platform of the reaper and are bolted thereto, as indicated at d d. The platform may be detached by simply removing these bolts and the connections with the driving and moving parts of the machine. The extension a is held to the permanent platform in like manner.

When the platforms are in place, as shown in Fig. 1, the rakes B of the reaper, of ordinary construction, sweep the gavel around and push it directly across the binder-platform A. The rakes therefore separate the grain for each gavel on a line between the standing and the cut grain, where alone complete separation is practicable, and no other mechanism is required to convey the grain from the reaper-platform to the binder-platform than the ordinary rake of the reaper. The gavel having been laid upon the binder-platform, it is moved to the rear by the tines 1 of the conveyer-chains E, which run over sprocket-wheels e e'. The construction of the chains is shown more clearly in Fig. 5. The tine is fixed to the connecting-bolt 2, and to the same bolt (extended beyond the links) and on each end is fixed an arm at right angles to the plane of the tines. Small outwardly-turned ends of these arms carry anti-friction rollers 3, which run in grooves

4 4 in the edges of the slot in the platform, and when so running hold the tine in a vertical position. At the rear end of the grooves in the slot of the platform the rollers 5 3 3 drop, as shown in Fig. 3, and throw the tines down. This occurs, as indicated in the figure last specified, when the gavel has been brought within reach of the needle. The tines return to the front, thus hanging loosely, and 10 are not in a position to be entangled with the grain, but are brought up into position over the sprocket-wheel *e*. The position of the tines against the gavel is shown in Fig. 4.

Intermittent motion of the conveyer at the 15 proper moment is caused by the rake, which moves the gavel to the binder-platform. The conveyer-chains are driven by the sprocket-wheels *e' e'*, fixed on the shaft *f*. On the outer end of this shaft runs loosely a sprocket-wheel, 20 5, driven by a chain, 10, from the sprocket-wheel *R* on the main axle *F'*. This wheel 5 is connected to the shaft by means of a clutch, 6. A lever, 7, Fig. 1, pivoted beneath the frame, is connected to a lever, 9, Figs. 1 and 25 2, by means of a rod, 8. The upper end of the lever 9 stands in the path of the rake *B*, which reaches the lever just before it rises, and moves, by means of the lever, the clutch 6 into gear with the wheel 5. This wheel runs 30 constantly, and the clutch-connection with the shaft causes it at once to start the conveyer. This moves the gavel to the binding mechanism, which must then be brought into action.

The needle *G* is on the end of the rock-shaft 35 *g*, having its bearings near the rear end of the binder-platform. A shaft, *H*, mounted in standards 11 on the rear of the platform, carries the frame *m*, which supports the tying mechanism *N*, and the wheel *h*, which drives 40 the latter. This wheel is fast on the shaft; but the sprocket-wheel *k* is loose on the same shaft and is driven continually by the chain 10. Outside this wheel is a clutch, 12, fixed to the shaft *H*, the teeth of which clutch face 45 corresponding teeth on the outer face of the wheel *k*. The latter slides on its shaft into and out of mesh with the clutch-teeth, and the wheel is thus moved by means of a lever, 13, pivoted on a stud underneath the platform and 50 extending, as shown in Figs. 1 and 6, within range of one of the anti-friction rollers secured to the tines. Connection between the lever 13 and the hub of the wheel *k* is made by means of a link, 14^x, and a bell-crank-lever, 14, one 55 end of which is forked and embraces the hub, and the other is pivoted to the upper end of said link 14^x. This downward movement of the inner end of the lever 13 will tip the bell-crank lever 14, and throw its upper end outward, thus throwing the wheel *k* into engagement with the clutch 12 and starting the shaft *H*. This sets the tying mechanism in operation, as hereinafter fully explained. The clutch remains in engagement until re- 65 moved by means of a spring-arm, 15, which is on the binder rock-shaft *g*, near its outer end, and in such position that when the needle

is returning, after the completion of the tying operation, this spring-arm strikes the lever 13 near its outer end and tilts the bell-crank 70 lever in the direction opposite to that first described and throws the driving-wheel *k* out of engagement with the clutch 12. As will appear from Figs. 1 and 10, the driving-chain passes under the wheel 5, over the wheel *k*, 75 and down under the idle-wheel *l*, back to the main sprocket-wheel *R* on the axle *F'* of the main drive-wheel *F*, a single chain moving all the mechanism involved in the binding operation and handling the grain after it 80 leaves the rake.

In my tying mechanism I use what is known as the "Appleby frame," with its stripper and knife. This frame *m* need not, therefore, be particularly described. It is shown in Figs. 85 3, 4, 6, and 8, being hung on the shaft *H* and held stationary by means of a rod or rods, 16. In the cross-bar 17 of the frame is hung the knotter *N*. The form of this knotter is shown in Figs. 8, 11, 12, 13, 14, and 15. It is turned 90 on a shank, 18, by means of a pinion, 19, on its upper end. The knotter has a horizontal arm, 20, in the form of a flat bar, its sides in planes parallel with the shank and its edges rounded. The angle of the knotter is formed 95 with a throat, 21, and swell 22, the latter being shown more clearly in Figs. 8 and 11. The knotter is hung on the left-hand side of the wheel *h*, and the knotter-arm 20, when in position to commence the operation of tying, 100 extends directly across and just beneath the path of the needle. In this position the swell 22 is on the side toward the needle, and the parts are in the position shown in Figs. 7 and 12. The swell begins from the line occupied by 105 the cord in Fig. 11, and overhangs that position. The arm 20 is bored longitudinally to receive a small shaft, on one end of which is a finger, 23. This is adapted to turn over and close a notch in the end of the arm 20, as 110 shown in Figs. 7, 8, 14, 15, and 17, or to turn away and open said notch, as shown in Figs. 11, 12, and 13. Other fingers, 24 and 25, are fixed on the opposite end of the shaft. Of 115 these, finger 25 limits the movement of the shaft one way by contact with a stop-pin, 26, Fig. 11, and moves it the other way by contact with a stud, 60, as hereinafter explained. The other finger, 24, imparts movement to the shaft to shift the finger 23 back to open the 120 notch by contact with the stripper, both movements being effected during the turning of the knotter, as hereinafter more particularly explained.

The needle-shaft *g*, which is connected to 125 the shaft *H* by crank-arms 27 and 28 and rod 29, is started by means heretofore described as soon as the gavel is within reach of the needle, which swings up from front to rear from a position shown in Fig. 4 to that shown in 130 dotted lines in Figs. 11 and 14. It carries the cord around the gavel, as shown in Figs. 3 and 12, one end of the cord being in a holder, preferably of the Appleby form. This complete

movement of the needle lays the cord above the arm 20, and also carries it through a notch in the holding-disk 28. This disk is pivoted on an arm, 28^a, in rear of the knotter, as shown in Figs. 7 and 8. The end of the needle has a shoulder, 129, underneath which the cord passes, and as the shoulder passes the disk, Fig. 11, the cord is delivered into the notch *x*, Fig. 7, and the disk is turned, carrying the cord aside into a stationary holder, 30, which is grooved to receive the cord and disk. This is a well-known form of holder. The disk is moved at the proper moment by means of a pallet, 31, hung from the pivot of the disk, 15 and operated by means of a rod, 32, connected to a lever, 33, one end of which projects into a cam-groove, 62, of suitable form in the face of the wheel *h*. Two folds of the cord are thus held—one, that which was carried through the notch *x*, as above described, and the other that previously left by the needle on its return-stroke—the end of the cord being held in the next preceding notch of the disk, and passing around through the same notch *x* to the needle. 20 The disk is immediately moved by the pallet, and the notch *y* is brought into the position first occupied by the notch *x*, so that the cord held in the holder 30 runs back through notch *y*, and is carried thence by the needle 25 around the next bundle and brought up again into the same notch *y*. Following the cam-groove in the wheel which operates the disk-lever (the wheel turning in the direction of the arrow, Fig. 8) is a segmental rack, which 30 rotates the knotter immediately after the cord has been gripped in the holder. This turns the knotter from the position shown in Figs. 7, 8, and 12 to that shown in Fig. 11, and thence quite around through the position 35 shown in Fig. 14 to its original position, as shown in Fig. 15. The doubled cord is held, as shown in Fig. 11, with that part of said cord extending to the holder and which is in rear of the arm 20, on a line with the notch in 40 the end of said arm, and with the part in front which extends around the bundle descending, so that as the knotter turns, the arm first crosses the sloping part of the cord, that part passing around the bundle, and then as 45 the knotter turns farther, the cord leading to the holder passes into the notch and is covered by the finger 23, as shown in Fig. 14. The knotter-arm 20 then moves to its original position parallel with the rear of the machine 50 and pointing to the left, as shown in Fig. 15. This finger 23 is operated during the movement by the finger 25 engaging the stud 60 on the cross-bar 17, which presses it down at the proper moment to cover and hold the cord. 55 The stud 60 is in front of the knotter and close to it, so as to be in the path of the finger 25 as the knotter turns. In passing under this stud 60 the finger 25 is turned down in a horizontal position, which brings the finger 23 over the notch. 60 The parts described are so placed that this occurs just after the arm 20 has turned sufficiently to bring the cord into the notch.

The finger 23 remains in this position till the knot is formed; but the finger 25 slips past the stud 60 before the knotter-arm has reached its original position. The reverse movement of the finger 23, caused by the stripper, is as follows: The form of the stripper *S* is modified to perform this function. In main features it is of the old form used prior to my invention. It is 70 on a bell-crank lever pivoted on a stud on the frame *m* at 37, with an anti-friction roller projecting into the cam-groove 61, which operates the stripper immediately after the revolution of the knotter. The rear of the stripper-flange 80 36 is so formed that, as it goes back after pushing off the loop, it strikes with its inclined side against the finger 24 (then projecting directly downward) and pushes it slightly aside, and there remains, bearing against it. This is 85 the position shown in Figs. 7 and 8, and the movement is sufficient to turn slightly aside the finger 23 and allow the cord to drop out of the notch. When the knotter moves again to form another knot, the finger 24 is dragged 90 over the edge of the stripper, and the finger 23 is further moved. The cord leading to the holder acts in the same direction and completes the movement of the fingers 23 and 24 to a horizontal position, quite opening the 95 notch for again catching the cord. The position of the cam-grooves is such that the disk is first caused to move the cord into the fixed holder. Then follows the segmental rack, which turns the knotter, and after this the 100 cam-groove of the stripper is operated in the manner described. The knotter is turned one complete revolution while the segmental rack is passing, and is held by a delay-surface on the lower part, 63, of the pinion, which bears 105 on a smooth rib, 64, extending around the wheel, excepting in that part opposite the segmental rack.

I have shown two cam-grooves in the wheel *h*; but one may be used instead, and the stripper *S* and the lever 33 both be worked from that one. 110

It will be observed that space is left between the knife 35 and the stripper for the knotter to turn in; but as the knotter-arm 20 turns, it 115 brings the finger 24 against the cord and opens fully the notch by turning the finger 23 to a horizontal portion.

The action of the compressor-plates (shown in Figs. 3, 4, and 12) takes place previous to the tying. The lower plate, 40, is pivoted above the shaft *g* of the needle, and is lifted by an arm on that shaft through a link, 41, bearing against the under side of the plate. The upper plate is composed of two parts, 42 120 and 43, the former bolted to the frame *m*, and the latter hinged to the former and operated by means of a rod, the bent end of which travels in a cam-groove, 44, in the face of the wheel *h* opposite to that before described. 125 Both plates 42 and 43 are slotted to let the needle pass through.

The complete discharge of the sheaf is effected by means of arms 47 on the shaft *H*, 130

Ordinarily this operation is performed so rapidly that the grain is thrashed out. In order to avoid this I have placed these arms upon the shaft H, which moves slowly, and therefore only pushes the sheaf sufficiently to cause it to drop from the rear of the platform. The arms are placed on the shaft in proper position to follow with their action the operation of tying. The stopping of the shaft which drives the tying mechanism at the proper instant is determined by the spring-arm 15, heretofore described.

The conveyer requires to be arrested when the tines have returned to the front and are ready to receive another gavel. This is accomplished by means of an inclined arm, 49, on the rod 8. This is struck by the tine 1 as it rises around the front sprocket-wheel, e, and pushes the rod to the left, thus throwing the clutch 6 out of engagement with the sprocket-wheel 5.

In order to allow space for the passage of the butts of the gavels, I provide a gate, P, Figs. 1 and 2. This is hinged at the junction 25 of the platform *a* and the permanent platform of the reaper, and is adapted to fall back and lie flat on the platform *a*. An arm, 50, on the gate extends down through the platform and is connected by a rod, 51, to one end of a bell-30 crank lever, 75, pivoted underneath. The other end of said lever 75 extends through a hole in the rod 8, and when the rod is drawn to throw the clutch into position to start the conveyer, the gate is thrown down to the rear and a clear passage is left for the conveyer to take the gavel to the rear. The reverse movement of the rod 8 to arrest the conveyer lifts the gate to its place, and then it serves to guide the gavel to the conveyer.

40 The position of the driving and supporting wheel F is clearly shown. The prolonged axle F' supports and drives the main sprocket-wheel R.

The binder-platform is supported by its 45 rigid connections to the main platform by the caster-wheel S and by a rigid connection at 130 between the main platform and the frame of the supporting-wheel. The platform is therefore supported against tipping and the 50 tongue is pivoted, and thereby the necks of the horses are relieved from the weight and jolting of the machine.

Having thus described my invention, what I claim is—

55 1. In combination with the platform of a reaper and its sweep-rake, a rigidly-attached binder-platform having a grain-conveyer and

having, also, a binding and tying mechanism on the rear of said binder-platform, a gate located on the reaper-platform, and the described mechanism for opening said gate when the gavel is removed to the rear, substantially as described.

2. In combination with a conveyer and binding mechanism, the sprocket-wheel R on the main drive-wheel axle F', the sprocket-wheels 5 and *k*, the idle-wheel *l*, and the driving-chain 10, arranged in relation to the specified parts in the machine, all substantially as set forth.

3. In combination with a binding mechanism, the shaft H, carrying the knotter mechanism, and devices to operate the same, the clutch connecting said shaft with a constantly-running driving-wheel, the conveyer, and actuating mechanism between the clutch and conveyer, whereby the conveyer when delivering the gavel sets the binding mechanism in operation, substantially as described.

4. In combination with a conveyer-clutch 80 and shifting lever, the rod connected to said lever and having an inclined arm, and the tine of the conveyer, whereby the tine is made to throw the clutch out of engagement, substantially as described.

5. The knotter N, having a horizontal arm with a notch in the end, the swell or overhang at the angle, the shaft with finger 23 covering the notch, and the fingers 24 25, in combination with devices, substantially as described, 90 for rotating the knotter and for rocking the finger-shaft.

6. The combination of the knotter containing the shaft provided with fingers and the stripper having the knife 35 and the flange 36, 95 the latter being adapted to operate the finger of the knotter, substantially as described.

7. In combination with the conveyer, the needle and the tying mechanism, the compressor-plate 40, pivoted above the needle-shaft, the rod 41, bearing against the under side of the plate, the upper plates, 42 and 43, constructed and arranged as described, the knotter-driving wheel having a cam-groove, 44, and the rod with its end traveling in said cam-groove, all as set forth.

In testimony whereof I have signed my name to this specification in the presence of two subscribing witnesses.

JOEL E. GILES.
